EDWIN TAYLOR, OF BROOKLYN, NEW YORK, ASSIGNOR TO TAYLOR LABORATORIES, INC., OF NEW YORK, N. Y., A CORPORATION OF NEW YORK.

TREATMENT OF ORGANIC MATERIAL.

Application filed July 2, 1924. Serial No. 723,654.

My invention relates to improvements in the treatment of organic material and more particularly to the treatment of cellulose material for making sheets or films of non-fibrous cellulose adapted for various uses. The main object of the invention is to provide a method whereby said sheets or film may be formed continuously in an efficient and economical manner. Further and more specific objects, features and advantages will more clearly appear from the detail description given below taken in connection with the accompanying sheets of drawings which form a part of this specification. In the drawings Fig. 1 is a vertical section largely diagrammatical, through a portion of an apparatus embodying my improvements in a preferred form thereof. Fig. 2 is a similar view showing another portion of the apparatus and Fig. 3 is a detail illustrating one method of controlling the flow of dissolved cellulose or organic material to the supply trough of Fig. 1.

Referring to the drawings, 4 represents a drum of substantially the width of the sheets or film to be produced, said drum being journaled at 5 and provided with a nickel plated copper peripheral surface. The journals of the drum 4 are supported by frame work 6 and the drum is driven by means of a worm 8 driving a worm gear 9 secured to the drum, the worm 8 being driven by a worm gear 10 meshing with a worm on a shaft 11 to which is secured a belt pulley 12 driven from any suitable source of power. Underneath the drum 4 and into which the drum 4 dips, is a shallow trough 12 supported upon suitable supporting blocks 13. Extending around the drum 4 and fitting closely to the sides of the drum 4 but spaced slightly from the periphery thereof, is a stationary casing 15. 16 represents a gas burner in a pipe 17, which pipe 17 is enclosed by a cylindrical metal member 18 perforated at 19 and open at the top at 20, whereby the heated pipe 17 heats the air surrounding the same in the cylinder 18 causing the air to be drawn in through perforations 19 and heated and passed out upwardly through the passageway 20 to the space between the drum 4 and the surround-

ing enclosure 15 as indicated by the arrows in Fig. 1. 22 indicates a wool covered wooden roll dipping into a trough of dilute sulphuric or nitric acid 23.

The operation of the parts so far described may be as follows. A solution of cellulose, for example cotton or other cellulosic material dissolved in a metal ammonia solution, such as a cupro-ammonia solution, is placed in the trough 12 and the drum 4 slowly rotated therethrough whereupon the surface of the drum picks up a layer of solution and carries it directly over the hot air from the passageway 20. The layer of cellulose solution on the drum continues in contact with this warm air as the drum rotates until the drum has rotated nearly a whole revolution. This subjects the cellulose solution to evaporation whereupon it increases greatly in stiffness and so that it may be mechanically handled like a film or sheet. The film passes around the roller 22 whereby it is caused to pass through the dilute acid 23 which more or less hydrolyzes the cellulose rendering it somewhat tougher and less liable to break in handling. The film (indicated at 24) then passes from the roll 22 over a roll 25. The roll 22 causes the film to be stripped from the drum 4 and the surrounding chamber 15 is extended at 26 and 27 and the warm air follows the path of the film until it passes out through an exhaust opening 28. The roll 25 is driven by means of a worm 29 on shaft 30 and intermediate gears 31 from the shaft on which the worm gear 10 is located.

After passing over the roll 25 the film or strip of somewhat hardened cellulose solution passes through an electrolytic tank or cell 32. For this purpose the tank is provided with a series of rolls 33 at the bottom of the tank and a series of rollers 34 at the top of the tank over which the film alternately passes back and forth up and down in the tank until it leaves the tank over roller 35. 36, 36 represent a plurality of lead or lead antimony anode electrodes lying between alternate turns of the film 24 and 37, 37 represents a series of copper cathodes on the opposite sides of the turns of the film from the anodes 36. As shown the lead

anodes 36 are connected to a common buss bar 38 and the cathodes 37 are connected to a common buss bar 39. The electrolytic cell 32 is filled with a suitable electrolyte such as dilute acid or ammonium nitrate and the electrodes being energized as the film or strip passes therethrough, the current will pass between the electrodes, through the film and cause the copper or metal solvent constituent in the cellulose to be removed by electrolytic action and deposited on the copper cathode freeing the ammonia which is given off as the gas and which by suitably covering the cell and conducting the ammonia away, may be condensed and recovered for re-use. The cell 32 is provided with a valved drain-off pipe 40 and the bottom of the cell is inclined toward this drain-off so that any sediment which may collect will 20 be carried toward the drain-off and may be easily removed.

From the roll 35 the film or strip of cellulose passes over a roll 41, down into a tank 42 containing wash water. The film 25 passes under a roll 43 in the bottom of the tank and up out of the tank over a roll 44. The tank is provided with a central partition or baffle 45 extending down nearly to roll 43. Wash water is run into the tank 30 through pipe 46 and allowed to overflow through pipe 47 so that wash water travels through the tank in a direction counter to the movement of the film therethrough. This washing substantially frees the film 35 of chemicals from the electrolytic tank 32. A valved drain pipe for the tank 42 is shown at 48.

For certain purposes the film may be treated with caustic soda. For this purpose 40 the film is shown running from the roll 44 over a roll 49 down into a tank 50 filled with caustic soda solution, say of specific gravity of 1.2 to 1.3, the film passing under the roll 51 in the bottom of the tank and 45 then up and out over roll 52. The tank 50 is shown as provided with a valve drain off pipe at 53. The tank 50 is provided with steam heating pipes 50^a in order to heat the solution therein when and to the extent 50 desired. This treatment with caustic soda may be used to produce various effects in the cellulose film or sheet as described in my copending application Ser. No. 720,525 filed June 17, 1924.

55 From the roll 52 the film is shown as passing over roll 70 and under rolls 59 and up over rolls 60, alternately, in a wash tank 53 (see Fig. 2). The wash water is continuously introduced through pipe 62 and overflows through pipe 63. The tank is provided with baffle partitions 64 extending upwardly from the bottom of the tank and with downwardly extending movable baffle partitions 65 adapted to slide up and down 60 in grooves in the side walls of the tank and

carrying at their lower ends the journals in which the rolls 59 are journaled. The baffles 65 may be easily lifted by rods 68 attached to the tops of the baffles having rings 66 at the upper ends thereof. The rods 65 pass 70 through transverse members 67 supported on the top of the tank and are held in adjusted position therein by set screws 69. The baffles 64 and 65 cause the wash water to travel up and down in the tank and flow 75 therethrough in a direction counter to the movement of the film through the tank so that it is given a thorough washing to remove surplus chemicals therefrom.

From the roll 57 I next preferably pass 80 the film strip down into a tank 61, under a roll 56 in the bottom thereof and up out over a roll 54. I preferably treat the cellulose film in the tank 55 with a solution of glycerine and water which serves to render 85 the film tough and elastic and for this purpose the tank 61 may be filled with a solution of glycerine and water containing about 30% glycerine and 70% water. The solution is preferably heated as by steam pipes 90 58. The proportions, etc. may be changed to produce various effects as described in my said copending application Ser. No. 720,525.

The cellulose film passes from the tank 61 over roll 54 and into a drying chamber 71 wherein it first passes around a small guide roll 72 and then around a large drum 73 and then in the opposite direction around another large drum 74, whence it passes 100 around a small guide roller 75, thence out of the drying chamber under a guide roller 76 and onto a take up reel 77. Warm air is caused to circulate over the cellulose film as it passes through the drying chamber in order to dry the film to the desired extent. The warm air is produced by means of a gas burner 78 in a pipe 79 whereby the air in the cylinder 80 surrounding the pipe 79 is heated. The air enters the cylinder 105 80 through apertures 81 in the bottom thereof and after being heated passes out through the top and through a passageway 82 into the main part of the dryer where by reason of the interposition of the travelling film it is caused to flow down under the drum 74 then up past the film through laterally extending by-passes 83 and over the top of the drum 73 in contact with the other side of the film and thence out 110 through the exhaust passage 84. 85 represents a glass covered window for inspecting the operation from the outside. The drums 73 and 74 are preferably open at both ends but run close to the sides of the drying chamber and I preferably make the periphery of the drums of monel metal.

In order to keep the level of the solution in the trough 12 at a substantially constant level, the method illustrated in Fig. 3 may 115

be employed wherein the trough 12 is shown connected with an elevated solution tank 86 by means of pipe 87 entering the bottom of the tank 86 and adapted to be closed by a valve 88 therein. The valve 88 is carried on a spindle 89 guided at the bottom by a guide 90 fixed thereto and operating in the pipe 87. The upper end of the spindle passes through the top of the tank 86 and 10 carries a collar 91 fixed thereto. Between the collar 91 and the top of the tank is a coiled compression spring tending to open the valve 88 and allow solution to run from the tank into the trough 12. Secured to the 15 upper end of the spindle 89 is the core or armature 92 operating within a solenoid electro-magnet 93 connected in circuit with a source of electric current 94 by means of switch 95. When the trough 12 becomes 20 filled to the desired height with the solution, the solution will complete the circuit through two contacts 96 in the end of the trough thereby energizing the solenoid, causing it to close the valve 88. When the 25 level of the solution in the trough 12 drops below the contacts 96 the circuit will be opened and the coiled spring will open the valve 88 thus regulating the supply of solution to the trough to maintain the level of 30 the solution therein substantially constant.

In case it is desired to impregnate the film with metal constituents or the like, the same may be accomplished by placing the treatment reagents in the tank 50. For example if it is desired to produce a substitute for tin foil, I preferably place in the tank 50 a solution of tin hydrate in caustic soda. This solution may be made by mixing about 1 volume of a suspension of tin 35 hydrate in water containing about 10% metallic tin, with 3 volumes of a 22% caustic soda solution. Then while the film is passing therethrough the solution of tin hydrate in caustic soda is boiled by heat from the steam pipes 50^a. With an ordinary thin 40 film or strip of the cellulose I preferably adjust the speed of the same so that it will remain in the boiling solution for about fifteen minutes. This causes the formation 45 of sodium stannate, and the deposition of metallic tin in the cellulose whereby the film is impregnated with metallic tin and gives to the film substantially the properties of tin foil except it is much stronger; 50 it being understood that after this impregnation with the tin, the film is passed through the glycerine bath and washed and dried as above described.

While I have described my improvements in great detail and with respect to a preferred embodiment thereof, I do not desire to be limited to such details or forms since many changes and modifications may be made and the improvements embodied in 60 widely different forms without departing

from the spirit and scope thereof in their broader aspects; hence I desire to cover all modifications and forms coming within the language or scope of any one or more of the appended claims.

What I claim as new and desire to secure by Letters Patent, is:

1. The method of treating cellulosic material which consists in passing a carrier through a solution of cellulosic material, 75 subjecting the solution to evaporation in the carrier to substantially increase the stiffness of the solution, and form a substantially continuous belt or strip of the solution, subjecting said belt or strip to the 80 action of dilute acid and removing same from said carrier, and passing the belt or strip through an electrolytic cell to remove solvent constituents from the cellulose material by electrolytic action.

2. The method of treating organic material which consists in passing a carrier through a solution of the organic material whereby the carrier picks up a layer of the solution, subjecting the solution on the carrier to evaporation to substantially increase the stiffness of the solution and form a substantially continuous strip of the solution, removing said strip from the carrier and 90 passing the same through an electrolytic 95 cell to remove solvent constituents from the organic material by electrolysis.

3. The method of treating cellulosic or organic material which consists in passing a carrier through a solution of the material 100 whereby the carrier picks up a layer of the solution, subjecting the solution to evaporation on the carrier to increase the stiffness of the solution and form a substantially continuous strip of the solution, 105 and without stopping passing said strip through an electrolytic cell to remove solvent constituents from the material electrolytically, and without stopping passing the strip through a wash water tank and 110 then through a drying apparatus.

4. The method of treating cellulosic or organic material which consists in passing a carrier through a solution of the material 115 whereby the carrier picks up a layer of the solution, subjecting the solution to evaporation on the carrier to increase the stiffness of the solution and form a substantially continuous strip of the solution, and without stopping passing said strip through an 120 electrolytic cell to remove solvent constituents from the material electrolytically, and without stopping passing the strip through a glycerine tank and a wash water tank and 125 then through a drying apparatus.

5. The method of treating cellulosic or other organic material which consists in passing a strip of the material containing a metallic element through an electrolytic cell to remove the metallic element from the 130

material by electrolytic action, and without stopping passing the strip through a wash tank and drying apparatus.

6. The method of treating cellulosic material containing a metallic element which consists in passing a strip of the material through an electrolytic cell to remove the

metallic element from the material by electrolytic action, and without stopping passing the strip through glycerine and drying ¹⁰ apparatus.

* In testimony whereof I have signed my name to this specification.

EDWIN TAYLOR.

material by electrolytic action, and without stopping passing the strip through a wash tank and drying apparatus.

6. The method of treating cellulosic material containing a metallic element which consists in passing a strip of the material through an electrolytic cell to remove the

metallic element from the material by electrolytic action, and without stopping passing the strip through glycerine and drying apparatus. 10

In testimony whereof I have signed my name to this specification.

EDWIN TAYLOR.

CERTIFICATE OF CORRECTION.
